UNITED STATES PATENT OFFICE.

JOHN V. CHAMBERLIN, OF WORCESTER, MASSACHUSETTS, ASSIGNOR TO
WEBSTER & CHAMBERLIN, OF SAME PLACE.

OSCILLATING ENGINE.

SPECIFICATION forming part of Letters Patent No. 240,657, dated April 26, 1881.

Application filed September 27, 1880. (No model.)

To all whom it may concern:

Be it known that I, JOHN V. CHAMBERLIN, of the city and county of Worcester, State of Massachusetts, have invented a new Improvement in Oscillating Engines, of which the following is a specification.

My invention relates to the arrangement of the ports and steamways in connection with an adjustable collar or steam-chest and a reversing valve or cock, the nature of which is shown in the following description and drawings of those parts of an engine embodying my invention.

In said drawings, Figure 1 is a side view of the cylinder and adjacent parts, with the reversing-valve shown in section. Fig. 2 shows the same as seen from above, the parts having the same letter in each.

A is the cylinder, oscillating in the usual way on the trunnion m, in a suitable bearing in the frame B.

w is a collar between the cylinder A and frame B, through which the steamways c c from each end of the cylinder are brought to the circumference. On this is fitted the steam-chest D, held in place by the cap C and adjusting-screws n n. The steam-chest D has three ports in its surface on w, the two outer, a a, connected together in one and with the other, e, forming two passages to the reversing-valve R. The two ports of w and three of D are set in the usual way, so that with the motion of the cylinder each one of w is alternately brought to match the middle one of D, and the other an outer one. The passages a e are given a quarter-turn before they get to R, so that it may stand at right angle to the trunnion m. The reversing valve or cock R is made with a central opening, g, for the discharge, having its aperture l fitted so as to be brought to either

passage a or e, and the outside of R is cut away to form a passage, f, from the steam-pipe k to the other.

By having the ports in the circumference of w and the use of the piece D the wearing-surface is equalized, and compensation can be made by the screws n n, and, if desired, the piece D can be set so as to give a lead to the ports either way, while by the arrangement therewith of valve R the passages a and e can either of them be made leader or discharge by turning the opening l from one to the other, which reverses the action of the piston, giving a reverse motion.

The other parts (not shown in the drawings) may be of almost any desired form and general arrangement in common use suitably adapted to the above, and therefore not needing further description here.

Having thus fully described my invention, what I claim as new therein, and desire to secure by Letters Patent, is—

1. In an oscillating engine, the reversing-valve R, provided with the passage f, and having central opening, g, provided with the aperture l, all constructed and arranged substantially as and for the purpose specified.

2. In an oscillating engine, the reversing-gear R, constructed, as described, with the passage f, central opening, g, and aperture l, in combination with the steam-chest D, all constructed and arranged substantially as specified.

In testimony whereof I hereunto set my hand this 24th day of September, A. D. 1880.

JOHN V. CHAMBERLIN.
